No. 34,543.

Patented May 21, 1901.

J. R. WILLIAMS.

TOP BED FRAME FOR CIGAR ROLLING MACHINES.

(Application filed Apr. 17, 1901.)

UNITED STATES PATENT OFFICE.

JOHN R. WILLIAMS, OF EAST ORANGE, NEW JERSEY, ASSIGNOR TO THE
JOHN R. WILLIAMS COMPANY, OF NEW YORK, N. Y.

DESIGN FOR A TOP BED-FRAME FOR CIGAR-ROLLING MACHINES.

SPECIFICATION forming part of Design No. 34,543, dated May 21, 1901.

Application filed April 17, 1901. Serial No. 56,322. Term of patent 14 years.

To all whom it may concern:

Be it known that I, JOHN R. WILLIAMS, a citizen of the United States, residing at East Orange, in the county of Essex and State of New Jersey, have invented and produced a new and original Design for a Top Bed-Frame for Cigar-Rolling Machines, of which the following is a specification, reference being had to the accompanying drawings, forming a part thereof, and in which—

Figure 1 is a top view of a bed-frame bearing and incorporating my design. Fig. 2 is a vertical transverse section of same on the dotted line 2 2 of Fig. 1, and Fig. 3 is a vertical longitudinal section of same on the dotted line 3 3 of Fig. 1.

The leading feature of my design consists of the form and configuration of the bed-frame, substantially as shown.

In the drawings, A designates the bed-frame as a whole, said bed-frame comprising the horizontal table portions B C, the latter being elevated above the horizontal plane of the portion B and disposed centrally of the rear portion thereof and having a curved front edge D. Vertical sides E E rise from the table portion B to the side edges of the

table portion C, as shown in Figs. 2 and 3, and the vertical sides E E are continued forward in the form of vertical flanges F F to 30 nearly the front edge of the table portion B, said flanges F F converging inwardly and confining a portion (lettered G) of the table portion B. At the front portion of the bed-frame and extending between the flanges F 35 F is an oblong-shaped depression or portion H. At its opposite sides the bed-frame A has the bordering flange I, and this flange is extended along the rear edge of the bed-frame, said flange at the opposite edges of the elevated table portion C ascending on graceful lines, as at J J, to the proper elevation to serve as a border along the rear edge of said table portion C.

What I claim is—

The design for a top bed-frame for cigar-rolling machines, substantially as shown and described.

Signed at New York, in the county and State of New York, this 15th day of April, 1901.

JOHN R. WILLIAMS.
